(57) **CLAIM**

The ornamental design for a mobile phone, as shown and described.

DESCRIPTION

FIG. 1 is a front view of a first embodiment of a mobile phone, showing our new design, in an off state;

FIG. 2 is a back view of the mobile phone of FIG. 1;

FIG. 3 is a left view of the mobile phone of FIG. 1;

FIG. 4 is a right view of the mobile phone of FIG. 1;

FIG. 5 is a top view of the mobile phone of FIG. 1;

FIG. 6 is a bottom view of the mobile phone of FIG. 1;

FIG. 7 is a bottom, front, right perspective view of the mobile phone of FIG. 1;

FIG. 8 is a bottom, back, left perspective view of the mobile phone of FIG. 1;

FIG. 9 is a front view of the mobile phone of FIG. 1, shown in a state of use;

FIG. 10 is a bottom, front, right perspective view of the mobile phone of FIG. 1, shown in the state of use;

FIG. 11 is a front view of a second embodiment of a mobile phone, showing our new design, in an off state;

FIG. 12 is a back view of the mobile phone of FIG. 11;

FIG. 13 is a left view of the mobile phone of FIG. 11;

FIG. 14 is a right view of the mobile phone of FIG. 11;

FIG. 15 is a top view of the mobile phone of FIG. 11;

FIG. 16 is a bottom view of the mobile phone of FIG. 11;

FIG. 17 is a bottom, front, right perspective view of the mobile phone of FIG. 11;

FIG. 18 is a bottom, back, left perspective view of the mobile phone of FIG. 11;

FIG. 19 is a front view of the mobile phone of FIG. 11, shown in a state of use; and,

FIG. 20 is a bottom, front, right perspective view of the mobile phone of FIG. 11, shown in the state of use.

1 Claim, 18 Drawing Sheets
